United States Patent Office

Des. 224,385
Patented July 25, 1972

224,385

BATHING CAP

Philip Allen Wilson-Haffenden, Deal, England, assignor
to W. W. Haffenden Limited

Filed July 10, 1970, Ser. No. 23,903

Claims priority, application Great Britain Apr. 22, 1970

Term of patent 14 years

Int. Cl. D2—03

U.S. Cl. D2—237

FIG. 1.

FIG. 2.

FIG. 1 is a side elevational view of a bathing cap showing my new design, the side opposite being substantially a mirror image thereof; and

FIG. 2 is a top plan view thereof.

I claim:

The ornamental design for a bathing cap, as shown and described.
